SLEEVE PULLER

William Henry Helton, Burns, Kans.

Application November 21, 1950, Serial No. 196,789

3 Claims. (Cl. 29—255)

1

My invention is directed to improvements in sleeve pullers of the impact type.

While the sleeve puller according to my invention is particularly adaptable to pull or extract sleeves of internal combustion engine blocks it may equally as well be used to pull other sleeves such as bearing mountings, races and the like.

It is an object of the invention to provide a sleeve puller which may be passed through a sleeve to be pulled from one end and engaged with the foot or inaccessible end of the sleeve through manipulation of an operating device extending through the body of the sleeve puller to the upper exposed and accessible end of the sleeve puller.

A further object of the invention is to provide in a sleeve puller an upper end of sleeve engaging plate with adjustable connecting means for connecting it to the body of the sleeve puller in a manner so that it is tightly set against the upper end of the sleeve being pulled.

A still further object of my invention is to provide in a sleeve puller an elongated hollow body member with a sleeve engaging means at its lower end operated to engage and disengage the lower end of a sleeve by an operating rod extending up through the hollow elongated body to the upper operating end thereof together with a top of sleeve engaging plate that is adjustably mounted along the elongated hollow body member and a slidable concentrically mounted impact member on the hollow elongated rod which may strike against the sleeve engaging plate and a head on the upper end of the elongated hollow body member.

A still further object of my invention is to provide in a sleeve puller a foot engaging means for the bottom end of the sleeve being pulled which has a housing connected to the lower end of an elongated hollow body member that is adapted to pass through the sleeve being pulled and has mounted in apertures in the housing, slide members which slide substantially transverse to the axis of the hollow body member and are biased to an inwardly slid position and moved to an outwardly slide position by means of a rod controlled wedge shaped operating member that engages inclined faces on the inner ends of the slide members when the operating rod is moved axially within the elongated hollow body member.

Still further objects and the entire scope of applicability of the present invention will become apparent from the detailed description given hereinafter; it should be understood, how-

2

ever, that the detailed description and specific examples are given by way of illustration only and, while indicating preferred embodiments of the invention, are not given by way of limitation, since various changes and modifications within the spirit and scope of the invention will become apparent to those skilled in the art from this detailed description.

My invention will be described in more detail hereinafter in conjunction with the accompanying drawings, in which:

Figure 1 is a side elevation of the sleeve puller in attached position with a cylinder sleeve as it is being pulled out of a cylinder block mounting;

Figure 2 is a vertical cross section of the sleeve puller shown in Figure 1 with the sleeve being pulled and its mounting block omitted;

Figure 3 is a vertical cross sectional view similar to Figure 2 showing a modified form of mounting the top of sleeve engaging plate on the elongated hollow body of the sleeve puller; and

Figure 4 is a somewhat enlarged cross sectional detail view of the lower end of sleeve engaging foot of the sleeve puller.

The particular illustration of use of the sleeve puller according to my invention is in pulling a cylinder sleeve 10 mounted in a block 11 of an internal combustion engine. Other sleeves and races as heretofore referred to may equally as well be pulled or backed out of their seated mounting with my sleeve puller. The upper end of the cylinder sleeve is indicated at 10' and the foot or lower end 10'' which is within the cylinder block and is relatively inaccessible.

The sleeve puller is generally indicated at 12 and is inserted through the upper end 10' of the sleeve 10 to be pulled or backed out of the block 11. The sleeve puller is built up about an elongated hollow body rod 13 which is common to all figures of the drawings. The lower end of this rod 13 has attached a foot or bottom of sleeve engaging assembly generally indicated at 14 and shown in enlarged detail in Figure 4.

This foot engaging assembly 14 comprises a hollow open ended cup-like housing 15 having a threaded aperture 16 in its base 17 which is threadedly connected to the threaded lower end 13' of elongated hollow rod 13. A lock nut 18 securely holds the housing 15 in position on the end of rod 13. Housing 15 is provided with a plurality of apertures 19 in its wall which apertures extend substantially transverse to the longitudinal axis X—X' of the elongated hollow rod 13. There is illustrated, for example, in Fig-

ure 4 the two oppositely disposed apertures 19—19 within which are slidably mounted slide elements 20—20.

The slide elements 20 are formed with a depending portion 20' and with their inner ends formed with outwardly and downwardly inclined faces 21 in the form of tongues which are received in cooperating inclined grooves 22 in a wedge member 23 having a threaded central aperture 24 which is threadedly received on the lower threaded end 27 of a control rod 28. Control rod 28 extends up through the elongated hollow rod 13 where it is threaded at its upper end 29 to receive a knurled surfaced knob 30 which is held in fixed position by a lock nut 31. By rotating control rod 28 in a clockwise direction as viewed from its upper end, its threaded lower end 27 screws into the internally threaded wedge element 23 thus pulling the wedge 23 upward and forcing outwardly the slide elements 20—20 against biasing compression springs 25 seated in pockets 20'' in the depending portions 20' of the slide elements and with their outer ends pressing against the adjacent inner walls of housing 15. Thus, upon rotation or movement of the control rod in the reverse or opposite direction, the wedge element is moved downwardly permitting the biasing spring elements 25 to force the slides 20 back through their aperture mountings 19 in the housing 15. In Figures 1, 2 and 3 the slide elements are shown in extended position where they will engage the sleeve to be pulled 10 as by abutting its lower edge as shown best in Figure 1. Thus, upon forcing or driving the elongated rod upward, the sleeve 10 will be carried only with it and pulled out of its mounting as in the block 11.

Still referring to the foot engaging means 14, it will be observed that the foot engaging means 14 is of a sufficient diameter in size to fit within the sleeve 10. So also it will be noted that this foot engaging means attached to the lower end of rod 13 may be easily passed through the sleeve 10 from its upper end 10' and then the control rod 13 may be so moved or actuated that the slide elements 20—20 will be slid into the position of engagement with the sleeve 10 as shown in Figure 1 and as heretofore described.

The housing 15 may be fitted with a closure 32 in the form of a circular plate that is held in place by suitable securing screws 33 threaded into the walls of housing 15.

In order to securely fasten the sleeve puller within the sleeve, an upper end of sleeve engaging plate 35 is provided and it has a suitable recessed ridge 35' which engages the upper end 10' of the sleeve 10. Plate 35 is apertured and threaded at its center 36 and is adjustably connected to rod 13 intermediate the rods as will be described.

In Figures 1 and 2 one form of adjustably connecting plate 35 with rod 13 is shown. An elongated sleeve 37 is slid over hollow rod 13, concentric therewith, and has an externally threaded lower end 37' and an internally threaded upper end 37''. Center threaded aperture 36 in plate 35 is screwed onto the end 37' of sleeve 37 and is secured by means of a lock nut 38 having a pin tightening pocket 38' in the face thereof. The upper internally threaded end 37'' of sleeve 37 is screwed onto the threaded upper end 13'' of rod 13. In the relative position of parts shown in Figure 2, sleeve 37 is screwed all the way down on threaded end 37'' of rod 37, however, it may be adjusted by screwing it along

the threads so as to secure the proper spacing between the foot engaging means 14 and the plate 35. In the position of parts shown in Figure 1 it will be noted that the sleeve puller is secured tightly in place in sleeve 10 for the actuation of the impact hammer to be described.

Slidably mounted over sleeve 37 in Figure 2 and concentric therewith and with elongated hollow rod 13 is a relatively heavy hammer member 39 in the form of a cylinder with a longitudinally or axially extending center aperture 40 which is concentric with the elongated hollow rod axis X—X', see Figure 4. A pair of suitable operating handles 41—41 are secured to the hammer 39 in opposed position and transverse to the longitudinal axis by means of threaded stems 42 thereon which are received in threaded apertures 43 in the hammer member 39. This hammer member is made of steel and is suitably hardened to withstand the impact blows as are the other parts of my sleeve puller.

On the upper threaded end 37'' of the hollow rod 13 is threadedly secured a head 44 in the form of a nut which is provided with suitable pin receiving apertures as at 44' in which may be inserted a pin for turning the head. This head 44 serves as an anvil as does the plate 35 against which the slidably mounted hammer 39 may strike when manipulated by the operator grasping the oppositely disposed handles 41—41 thereon.

In the modified form of my invention as shown in Figure 3, there is illustrated another adjustable connecting means for the plate which fits 35 against the upper end 10' of the sleeve to be pulled and here designated plate 45. Plate 45 has a center threaded aperture 46 which is received on the threaded end 47 of a slidably mounted collar 48 on elongated hollow body rod 13. Suitable tightening screws 49 are threadedly mounted in threaded side apertures in the collar 48 and when screwed in against the hollow rod 13 hold the collar 48 tightly secured thereto. Additional securing means for the collar 48 is provided in the lock collar 50 mounted therebelow and likewise provided with securing screws 51.

I have provided in my sleeve puller, a mechanism that is easily attached to a sleeve to be pulled by inserting through one end thereof and securing it in the sleeve by operation of a control rod knurled knob 30 to set the foot engaging means. Also from the same end of the tool the upper end of sleeve engaging plates as at 35 and 45 may be tightly set up against the end of the sleeve 10 being pulled. After securing the puller in place in the sleeve 10, then the easily operated hammer 39 may be slid between the anvil, namely, plate 35 or 45 and head 44.

For sleeves of different size suitable larger or smaller foot attaching assemblies 14 and plates 35 may be used with the same operating and mounting mechanism.

Since it is obvious that certain further changes can be made in the foregoing constructions without departing from the spirit and scope of this invention, it is intended that all matter shown in the accompanying drawings or described hereinbefore shall be interpreted as illustrative and not in a limiting sense.

70 I claim as my invention:

1. In a sleeve puller, an elongated hollow rod having an externally threaded portion at its upper end; a hollow housing attached to the lower end of the hollow rod adapted to fit inside the sleeve to be pulled and having a plurality of aper-

tures therein extending substantially transverse to the axis of the hollow rod; a sleeve engaging means associated with said housing; a control rod extending through said hollow rod and connected with said sleeve engaging means whereby actuation of said control rod causes said sleeve engaging means associated with the housing to engage and disengage a sleeve to be pulled; said sleeve engaging means comprising a plurality of elements slidably mounted in said apertures of the housing and adapted in outwardly slid position to project beyond the confines of said housing to abut against the end of the sleeve to be pulled, biasing means urging the slide elements to slide in one direction in said housing apertures and means on the end of said control rod within the housing adapted to engage said plurality of slide elements to urge them in the opposite direction to said biasing means action when the control rod is moved in one direction and permitting the biasing means to move said slide elements in the opposite direction; a sleeve engaging plate having a threaded aperture at its center; means to adjustably connect said plate to said hollow rod intermediate its ends whereby the plate engages the opposite to said other end of the sleeve to be pulled comprising an elongated sleeve mounted over the hollow rod and having an internally threaded upper end in threaded engagement with said upper threaded end of the hollow rod and an externally threaded lower end for receiving the internally threaded sleeve engaging plate, whereby said elongated sleeve may be moved along said hollow rod by its threaded engagement with the hollow rod to position said sleeve engaging plate at a selected position intermediate the ends of the hollow rod; a head attached to the upper end of said hollow rod; and a hammer mounted concentric with said hollow rod for sliding movement between the sleeve engaging plate and the head whereby the hammer may strike the sleeve engaging plate and the head.

2. A sleeve puller of the character described in claim 1 wherein said biasing means urge the slide elements inwardly in the housing apertures, said inner end of said slides are inclined surfaces, said slide operating means on the lower end of the control rod is a wedge element having inclined surfaces in engagement with said inner inclined end surfaces on the slide elements whereby movement of said control rod in one direction moves said wedge element attached thereto into engagement with said inclined ends on

the slides to force the slides outwardly against said biasing means while movement of the control rod in the opposite direction permits said biasing means to move said slides inwardly.

- 5 3. In a sleeve puller, an elongated hollow rod, a sleeve engaging foot means positioned at the lower end of said hollow rod, a control rod extending through said hollow rod and connected with said foot whereby actuation of the control
10 rod causes said foot means to engage and disengage a sleeve to be pulled, a sleeve engaging plate, means to adjustably connect said plate to said hollow rod and hold the plate at a selected position thereon intermediate the ends of the hollow rod whereby the plate engages the opposite to the foot engaging end of the sleeve to be pulled, a head attached to the upper end of said hollow rod, and a hammer mounted concentric with said hollow rod for sliding movement between the sleeve engaging plate and the head whereby the hammer may strike the sleeve engaging plate and the head, said hollow rod has an externally threaded portion at its upper end, said sleeve engaging plate has a threaded aperture at its center and said means to adjustably connect said sleeve engaging plate to said hollow rod intermediate its ends comprises an elongated sleeve mounted over the hollow rod and having an internally threaded upper end in threaded engagement with said upper threaded end of the hollow rod and an externally threaded lower end for receiving the internally threaded sleeve engaging plate, whereby said elongated sleeve may be moved along said hollow rod by its threaded engagement with the hollow rod to position said sleeve engaging plate at a selected position intermediate the ends of the hollow rod.

WILLIAM HENRY HELTON.
